[57] CLAIM

The ornamental design for a ghost figure doll, or the like substantially as shown and described.

DESCRIPTION

FIG. 1 is a perspective view of a ghost figure doll looking at the front of my design as it would appear on a relatively flat surface;

FIG. 2 is a perspective view looking at the rear of my design as it would appear on a relatively flat surface;

FIG. 3 shows my design in elevation as it would appear hanging from a support or pinned to a vertical surface;

FIG. 4 shows my design in side elevation as it would appear hanging from a support or pinned to a vertical surface.
